US00D738194S

(12) **United States Design Patent**
Baldoni et al.

(10) **Patent No.:** **US D738,194 S**
(45) **Date of Patent:** **** Sep. 8, 2015**

(54) **REINFORCEMENT SUPPORT MEMBER**

(71) Applicants: **Edwin Joseph Baldoni**, Union Dale, PA (US); **Dario Joseph Baldoni**, Boston, MA (US)

(72) Inventors: **Edwin Joseph Baldoni**, Union Dale, PA (US); **Dario Joseph Baldoni**, Boston, MA (US)

(73) Assignee: **CONCRETE COUNTERTOP SOLUTIONS, INC.**, Clarks Summit, PA (US)

(**) Term: **14 Years**

(21) Appl. No.: **29/470,807**

(22) Filed: **Oct. 25, 2013**

(51) LOC (10) Cl. **08-05**
(52) U.S. Cl.

USPC **D8/354; D8/380**

(58) **Field of Classification Search**

USPC D8/354, 349, 380, 384; D25/199; 248/440; 52/677, 678, 679, 682, 684, 52/685, 686, 687, 745.21, 688, 689, 637, 52/649.1, 683, 633, 646, 649.8, 649.3, 52/645, 680; 404/134, 135, 136

(57) **CLAIM**

The ornamental design for a reinforcement support member, as shown and described.

DESCRIPTION

FIG. 1 is a perspective view of a reinforcement support member in accordance with our new design;

FIG. 2 is a front elevational view of the reinforcement support member shown in FIG. 1, the rear elevational view being the same;

FIG. 3 is a left-side elevational view of the reinforcement support member shown in FIG. 1, the right-side elevational view being the same;

FIG. 4 is a top plan view of the reinforcement support member shown in FIG. 1; and,

FIG. 5 is a bottom plan view of the reinforcement support member shown in FIG. 1.

The broken lines shown in the drawings represent portions of the reinforcement support member that form no part of the claimed design.

1 Claim, 2 Drawing Sheets
